UNITED STATES PATENT OFFICE.

JOHN T. QUIGLEY, OF BOSTON, MASSACHUSETTS, ASSIGNOR, BY MESNE ASSIGNMENTS,
TO POSTINDEX COMPANY, INC., OF BOSTON, MASSACHUSETTS.

FILING AND INDEXING EQUIPMENT.

Application filed July 14, 1919. Serial No. 310,691.

This invention relates to filing and indexing equipments of the class in which the sheets are arranged with their identification-receiving margins in overlapping relationship, and the invention aims to increase the leaf capacity of an equipment of a given compass, while still preserving the advantages of an index of the overlapping type.

My invention will be best understood by reference to the following description, when taken in connection with the accompanying drawings of one specific embodiment thereof, while its scope will be more particularly pointed out in the appended claims.

15 In the drawings:

Fig. 1 is a front elevation of a filing and indexing equipment exemplifying my invention;

Fig. 2 is a bottom plan view of one of the 20 groups of sheets and the sheet-holder therefor;

Fig. 3 is an elevation of a single group of several foldable sheets with their sheet-holder, the sheets being shown as they appear when unfolded, and exposing to view the inner face of the innermost sheet of the group;

Fig. 4 is a sectional view on an enlarged scale of one group of sheets and their sheet-holder, taken on line 4—4 of Fig. 1; and

Fig. 5 is a perspective view of one group of folded sheets with their sheet-holder, the leaves of the entire set being separated from one another for the sake of clearness.

35 Referring to the drawings, and to the filing and indexing equipment which is illustrated therein, I have selected for exemplification an equipment comprising a plurality of sheets arranged in overlapping groups. 40 Each group may comprise four or more leaves, and preferably each pair of leaves is formed by folding the sheet. When folded sheets are employed, and when each group comprises two or more folded sheets, the 45 latter are nested; that is to say, the fold of one sheet is introduced into the fold of another. This arrangement is well shown in Figs. 4 and 5, in which I have illustrated four sheets, designated, respectively, 6, 7, 8 and 9. The sheet 6 comprises two leaves 10 and 10'. The sheet 7 comprises two leaves 11 and 11'. The sheet 8 comprises two leaves 12 and 12', and the sheet 9 comprises two leaves 13 and 13'.

55 One or more of the sheets of each group

may be provided with letters, numerals, words or other symbols to serve as an index, and in the present example, I have provided the outer sheet of each group with an identification serving for that group. The several groups are arranged with their identification-bearing margins in overlapping relationship, as clearly shown in Fig. 1, and while the dimensions of the complete file are not substantially increased by the use of 60 a plurality of groups of leaves instead of the usual individual leaves, yet the capacity of the file is greatly increased. One important feature of this increased capacity is the use of a single sheet-holder for all the leaves of 65 one group, and whereas in the present example several folded sheets compose one group, there is provided a single sheet-holder for all such sheets, as clearly shown in Fig. 5, 70 wherein I have shown a sheet-holder 14. In 75 the present example, each sheet is provided with two perforations 15, best shown in Fig. 3, adjacent the line of the fold and preferably substantially bisected by such line. Preferably, the intermediate portion of the 80 sheet-holder is received within the fold of the innermost sheet, and said sheet-holder extends through the perforations 15 and has its terminal portions entirely outside of the 85 folds of the sheets, as well shown in Fig. 2. The terminal portions are herein provided 90 with cylindrical trunnions 16, which may be received in suitable bearings in an appropriate mounting.

In the present embodiment, I have shown 95 a mounting 17 having inwardly facing flanges 18, presenting opposed channels to receive the trunnions 16, the latter contacting with one another in a continuous series, as shown in Fig. 1, and being restrained 95 against longitudinal displacement in the channels by the provision of suitable upper and lower stops 19 and 20. The trunnions maintain overlapping margins of the groups in properly-spaced relationship, and since 100 they are cylindrical, they permit the sheets which compose a given group to be turned about the axis of such group, in order to expose either face thereof, and to render the 105 desired surfaces accessible for inspection and recording purposes.

It is evident from the foregoing that a number of leaves may be interlocked with the sheet-holder, and will occupy practically the space of a single card. Where an ex- 110

tended record under a single reference is required, the pages are thus multiplied. In this way, the capacity of the file is greatly multiplied.

Having thus described one embodiment of my invention, but without limiting myself thereto, what I claim and desire by Letters Patent to secure is:

1. In a device of the class described, the combination of a plurality of sheets arranged in a series of overlapping groups, a series of sheet-holders, one for each group of sheets, and a mounting presenting bearings in which said sheet-holders are mounted to turn to present said sheets in an up-standing or a depending position.

2. In a device of the class described, the combination of a plurality of sheets arranged in a series of overlapping groups, a series of sheet-holders, one for each group of sheets, and a mounting presenting opposed channels in which said sheet-holders are received and mounted to turn about parallel axes.

3. In a device of the class described, the combination of a plurality of sheets arranged in a series of overlapping groups, a series of sheet-holders, one for each group of sheets, and a mounting presenting opposed channels in which said sheet-holders are received, said sheet-holders being adapted to turn in said mounting about their respective axes.

4. In a device of the class described, the combination of a plurality of sheets arranged in overlapping groups, each group comprising a plurality of folded, nested sheets, each sheet having a single fold from end to end and being perforated adjacent the fold, and a series of sheet-holders, one for each group of sheets, each sheet-holder extending through the perforations of the sheets of its group and having a part received within the fold of the innermost sheet of such group and a part extending along the external surface of the outermost sheet beside said fold, and a mounting for said sheet-holders.

5. In a device of the class described, the combination of a plurality of sheets arranged in a series of overlapping groups, each group comprising a plurality of folded, nested sheets, a series of sheet-holders, one for each group of sheets, and a mounting presenting bearings in which said sheet-holders are mounted, said sheet-holders being adapted to turn in said mounting about parallel axes.

6. In a device of the class described, the

combination of a plurality of sheets arranged in a series of overlapping groups, each group comprising a plurality of folded, nested sheets, a series of sheet-holders, one for each group of sheets, each sheet-holder being received in part within the fold of the innermost sheet of its group, while another part of such sheet-holder extends along the external surface of the outermost sheet entirely without the folds of said sheets, and a mounting presenting opposed channels in which said sheet-holders are received.

7. In a device of the class described, the combination of a plurality of sheets arranged in a series of overlapping groups, each group comprising a plurality of folded, nested sheets, a series of sheet-holders, one for each group of sheets, and a mounting presenting opposed channels in which said sheet-holders are received, said sheet-holders being adapted to turn in said mounting about parallel axes.

8. In a device of the class described, the combination of a plurality of sheets arranged in a series of overlapping groups, each group comprising a plurality of folded, nested sheets, a series of sheet-holders, one for each group of sheets, received in part within the fold of the inner sheet of such group, and thence along the exterior surface of the outermost sheet entirely without the fold of such sheet and a mounting for said sheet-holders.

9. In a device of the class described, the combination of a plurality of sheets arranged in a series of overlapping groups, each group comprising a plurality of folded, nested sheets provided with perforations adjacent their folds, a series of sheet-holders, one for each group of sheets, received in the fold of the inner sheet of each group and extending through said perforations, and a mounting for said sheet-holders.

10. In a device of the class described, the combination of a plurality of sheets arranged in a series of groups having overlapping indexed margins, a series of sheet-holders, one for each group of sheets, and a mounting for said sheets, said mounting presenting guides in which said sheet-holders are mounted to turn about parallel axes, and by which said sheets are guided in a direction transverse to their overlapping margins.

In testimony whereof, I have signed my name to this specification.

JOHN T. QUIGLEY.
